VIBRATOR AND HANDLE THEREFOR

Edward M. Chappell, Chicago, Ill., assignor to
Bally Manufacturing Company, Chicago, Ill.,
a corporation of Illinois

Application February 18, 1936, Serial No. 64,537

8 Claims. (Cl. 306—6)

This invention relates to a vibrator, of the kind used in massaging, and an improved handle structure for mounting or holding the same.

The vibrator is of the type having a body formed preferably cylindrical and carries on its outer surface a plurality of studs, or buttons, adapted for use in attaching the body to various holders, and in the present instance to a handle type of holder.

10 The primary object of the invention is to provide an improved handle for mounting the vibrator.

Another object is to provide such a handle including a ring portion which serves to embrace 15 the vibrator body and includes means cooperating with the studs to hold the handle in a fixed position relative to the body.

Still another object is to provide such a handle which may be quickly and easily attached to or 20 be detached from the vibrator body, as desired.

Also it is an object to provide such a handle which is cheap and simple to produce and which will effectively serve the purposes for which it is provided.

25 Other objects will become apparent to those skilled in this art as the disclosure is more fully made.

Briefly, such objects are achieved in combination with a vibrator body carrying headed studs 30 or buttons by providing a handle having a ring shaped head adapted to slide over one end of the body and embrace the same, said ring being formed with slots to fit around the shanks of the studs to hold the ring against angular displacement relative to the body. The handle has a 35 rotatable part for abutting a set screw included in the handle firmly against the head of one of the studs, whereby detachably to lock the handle to the body.

40 In the accompanying sheet of drawings is illustrated a practicable form of the invention for purposes of the disclosure. In the drawing:

Figure 1 is a reduced scale, rear end view of the assembled vibrator and handle;

45 Figure 2, on the same scale, shows a general side elevational view of the vibrator and handle;

Figure 3 is a front end, elevational view, on the same scale, of the combination;

Figure 4 is a central, longitudinal sectional view through the handle, per se, shown full size; and,

Figure 5 is a full size, end elevational view of the handle, per se.

The vibrator 10 shown is cylindrical and at one end includes a boss 11 for detachably mount-

ing any suitable form of applicator 12 useful in massaging a part of the human body, responding to such treatment. Near its front, or applicator end, the body 10 securely carries a number of angularly spaced headed studs, or buttons 13, 5 which preferably all lie in the same plane.

The improved handle device comprises an integrally formed head 14 in the form of a ring having a diameter adapting it to fit slidably over the head end of the body 10 in as snug a 10 manner as possible. Said ring is formed with a plurality of slots 15 cut out from one edge, with each of the slots properly spaced to receive the shank of a stud 13 when the ring is slid onto the body. The ring to save weight is generally made 15 as narrow as possible but each portion thereof in line with a slot 15 is widened out by scalloped extensions as shown at 16.

The ring head 14 includes an integral neck portion 17 formed adjacent one of the slots 15, 20 said neck having a pocket 18 formed therein in registration with the said slot 15. This neck 17 is formed with an axial bore into which threadedly fits a screw threaded shank 19 carried on a block 20 serving to connect the neck 17 with a 25 handle 21. This handle is rotatably mounted in relation to the neck 17 and when it is turned it causes the block 20 to turn therewith. Since the screw shank 19 also must turn with the block it follows that by means of the turnable 30 handle 21 the screw shank 19 may be threaded into or be backed out of the pocket 18. The head of the stud 13 which enters the slot 15 and pocket 18 may therefore be clamped or unclamped by the set screw 19 as desired. In full 35 lines in Figure 4 is shown the stud locking position of the screw 19 and in the dotted lines the same is shown retracted.

It will thus be seen that an improved handle device has been provided for a vibrator body of 40 the type disclosed, which device is handy for the purposes intended. It can be quickly and easily applied or removed from the vibrator as desired and when in place firmly holds the vibrator in the sense that it cannot be displaced therefrom or shift relative thereto. This is important 45 since the vibrator vibrates at high speed.

It is the intention to cover herein all changes and modifications of the preferred example disclosed, which do not in material respects constitute departures from the spirit and scope of the invention as covered in the following claims.

What is claimed is:

1. The combination with a vibrator body having studs fixed to its outer surface in spaced rela- 55

- tion, of a holder for the vibrator comprising a head in the form of a loop adapted to fit slidably over the body, said loop including slots aligned with the studs to receive same, and means for fastening the holder removably to one of said studs.
2. The combination with a vibrator body having studs fixed to its outer surface in spaced relation, of a holder for the vibrator comprising a ring shaped head adapted to embrace the body, said head being formed with slots to receive the studs, the ring being provided with widened portions in line with the slots, and means for fastening the holder removably to one of said studs.
- 10 3. The combination with a vibrator body having headed studs mounted thereon in spaced relation, of a ring shaped head adapted to fit over the body, said head including slots to receive the shanks of the studs, and means including a handle for removably fastening the head to a stud.
- 15 4. The combination with a vibrator body having headed studs mounted thereon in spaced relation, of a ring shaped head adapted to fit over the body, said head including slots to receive the shanks of the studs, a neck portion included in the head and having a slot formed therein to engage over a shank of one of the studs, said neck also including a pocket to receive the head of the stud positioned in the neck, and a handle including means for detachably fastening the holder to the stud engaged by the neck.
- 20 5. The combination with a vibrator body having headed studs mounted thereon in spaced relation, of a ring shaped head adapted to fit over the body, said head including slots to receive the shanks of the studs, a neck portion included in
- the head and having a slot formed therein to engage over a shank of one of the studs, said neck also including a pocket to receive the head of the stud positioned in the neck, a turnable handle carrying a block including a set screw 5 threadedly carried in the neck, said screw engaging the head of the stud disposed in the pocket when the handle is turned in the proper direction to lock the head to the head of the stud.
6. The combination with a vibrator body having headed studs mounted thereon in spaced relation, of a ring shaped head adapted to fit over the body, said head including slots to receive the shanks of the studs, the head including a neck, a handle turnably mounted on the neck including 10 a set screw threadedly carried in the neck and adapted to engage the head of a stud to lock the handle to the body.
- 15 7. The combination with a vibrator body carrying headed studs in spaced relation and lying in substantially the same plane, of a holder comprising a ring to fit over the body and provided with slots to receive the studs with the heads thereof disposed outside the ring, and a handle attached to the ring.
- 20 8. The combination with a vibrator body carrying headed studs in spaced relation and lying in substantially the same plane, of a holder comprising a ring to fit over the body and provided with slots to receive the studs with the heads 25 thereof disposed outside the ring, a neck included in the ring and provided with a cavity to receive a stud and its head, a handle connected rotatably to the neck, and means operable by the handle and carried in the neck to lock the holder detachably with the stud embraced by the neck.
- 30 35

EDWARD M. CHAPPELL.
